UNITED STATES PATENT OFFICE.

LEONARD G. ATTENBOROUGH, OF IPOH, PERAK, FEDERATED MALAY STATES, AND
JOHN F. NEWSOM, OF PALO ALTO, CALIFORNIA.

LIP FOR DREDGE BUCKETS.

Application filed August 16, 1920. Serial No. 403,681.

To all whom it may concern:

Be it known that we, LEONARD GEORGE ATTENBOROUGH, British subject, residing at Ipoh, Perak, Federated Malay States, and 5 JOHN FLESHER NEWSOM, citizen of the United States, residing at Palo Alto, in the county of Santa Clara, State of California, have invented a new and useful Lip for Dredge Buckets, of which the following is 10 a specification in such full and clear terms as will enable those skilled in the art to construct and use the same.

This invention relates to a lip for dredge buckets and its object is to produce a lip 15 which shall be so constructed as to enable the dredge bucket to operate in stiff clay soil without having the clay stick in the bucket, and thereby prevent the load from dumping, and also to facilitate the disintegration of the clay in the subsequent treatment.

It will be understood by those skilled in the art that when digging in stiff clay ground, the clay will stick to the inside of the dredge 25 bucket, and in a short time it will fill it up in such manner as to prevent it from obtaining a fresh load each time the bucket passes down against the bank being dug. When this takes place, it is necessary to stop the 30 bucket line and clean the buckets before it is possible to operate the dredge.

In this invention the lip is so designed as to prevent the material dug from adhering to the bucket, by deflecting the material 35 away from the back of the bucket, which will leave a space in which water or soft material will collect between the mass of clay and the back of bucket, thereby facilitating proper dumping.

40 Another object of the invention is to prevent the mass being dug from being pushed against the inner side of the back of the bucket so firmly that air or water cannot get in to allow the dumping when the bucket 45 goes over the upper tumbler of the bucket ladder.

Another object of the invention is to provide means whereby the clay being dug will be broken up into smaller pieces as the 50 bucket digs up its charge, thus further facilitating dumping of the clay from the buckets, and its subsequent disintegration.

A further object of the invention is to break up the material so that it will pass 55 into the bucket in a more or less separated

mass, mixed with water, whereby it will dump more freely.

Other objects of the invention will appear as the description proceeds.

An embodiment of the invention is shown 60 in the accompanying drawings in which the same reference numeral is applied to the same portion throughout, but we are aware that there may be modifications thereof.

Fig. 1 is a view of the bucket in the plane 65 of its mouth taken on the line 1--1, Fig. 2.

Fig. 2 is a sectional view of the bucket looking at right angles to Fig. 1.

Fig. 3 is a plane view of the bucket looking at right angles to the plane of its mouth 70 on the line 3--3, Fig. 4, showing a slightly modified form of bucket lip, and

Fig. 4 is a sectional view of the bucket looking at right angles to Fig. 3.

Fig. 5 is a sectional view showing detachable projecting cutting ribs, which may be removed from the bucket lip and replaced. 75

Fig. 6 is a top view of the detachable cutting rib shown in Fig. 5.

While it will be understood that the improved lips may be attached to any type of dredge or elevator bucket, the bucket shown in Figures 1 and 2 is one especially adapted for and in common use on endless chain dredge systems, but may be of any desired 80 type. It comprises the bucket body 1, with two heavy lugs 2 and 3 for connecting it to the next adjacent bucket, and it has an eye 4 to receive the pin passing through the lugs 85 of the other adjacent bucket. 90

The front edge of the bucket is recessed to take a horse-shoe shaped lip 5. Said lip in this invention is provided with a projecting flange at 6 for connecting it to the bucket, and has a raised portion or shoulder at 8 higher 95 than the back of the bucket, to prevent the material being scooped up from passing directly against the back of the bucket. Since the bucket is ordinarily worked under water, it will always mean that there is a body of 100 water between the mass being dug and the back of the bucket.

In order to break up the clay, the bucket lip may have a plurality of fixed or detachable cutters 9 projecting outwards therefrom which tend to cut the clay mass into longitudinal ridges so that comparatively small pieces are picked up by the bucket following. It may also be provided with an inward projecting cutter or rib, 10, for 110

cutting the clay into strips as it enters the bucket.

In the form of the invention shown in Figs. 3 and 4 the ordinary dredge bucket is illustrated at 10, lugs for connecting the bucket to the next adjacent bucket at 11 and 12, and the bottom eye is indicated at 13. The improved lip as shown on this bucket, 14, had a curved portion at 15 similar to 10 that used in the other form of bucket, but the raised portion of the lip is provided with a plurality of channels, 16.

The channels, 16, serve to permit the retention therein, while the digging is taking place, of soft material and water, and thereby tend to loosen the clay from the bucket lip and bottom.

It will be understood that the projecting cutters or ribs as shown at 9, may also be attached to this form of lip.

It will be noted that the curve or angle of the lip is such that the material passing thereover is cut to a different curve or angle from that of the bucket back, thereby assisting in preventing the material from being pushed solidly against the bottom of the bucket.

It will be further noted that the cutting ribs may be cast either as a part of the bucket lip or may be made detachable, as illustrated in Fig. 5, and that these cutters may also be provided with an inner projecting vane which will cut the clay into strips as it enters the bucket.

Having now particularly described and ascertained the nature of our said invention and in what manner the same is to be performed we declare that what we claim is as follows, but various modifications may be made in the construction shown in the drawings and above particularly described form, within the purview of our invention.

1. A lip for dredge buckets having a flange extending under the bucket, means 45 to secure the lip to the bucket at the ends

of the lip, the inner surface of the lip being smoothly formed without shoulders or interruptions from the front edge of the lip to the front edge of the bucket and positioned so that an extension thereof will direct material passing thereover into the bucket away from the bottom of the bucket and toward the back of the bucket. 50

2. A lip for dredge buckets comprising a lip having an extended cutting face, means 55 at the ends of the lip to secure the same to the bucket, a flange on the lip extending under the bucket, that portion of the lip at the edge of the bucket being raised above the bottom of the bucket and smoothly 60 formed without shoulders to direct material passing into the bucket away from the bottom of the bucket and toward the back of the bucket.

3. A lip for dredge buckets comprising 65 a detachable cutting member extended across the mouth of the bucket, means to secure said lip in place, said means comprising bolts at the ends of the lip, and a flange extending therefrom under the bucket bottom, the body 70 of the lip being of different thicknesses in different portions both longitudinally and transversely.

4. A lip for dredge buckets comprising a detachable member having a plurality of projecting cutting ribs, a flange extending from the lip under the back of the bucket, said lip being raised immediately adjacent the bucket so that material passing thereover will be directed away from the bottom of 80 the bucket and toward the back of the bucket, said lip being of gradually increasing thickness from its front portion to the front edge of the bucket and of varying thickness longitudinally. 85

In testimony whereof we have hereunto set our hands this 14th day of April, A. D. 1920.

L. G. ATTENBOROUGH.
J. F. NEWSOM.
